WEFT-FEELER MECHANISM FOR LOOMS.

1,238,378.

Specification of Letters Patent. Patented Aug. 28, 1917.

Application filed December 30, 1915. Serial No. 69,477.

To all whom it may concern:

Be it known that I, EUGENE H. BALLOU, a citizen of the United States, residing at Pawtucket, in the county of Providence, 5 State of Rhode Island, have invented a certain new and useful Improvement in Weft-Feeler Mechanisms for Looms, of which the following is a specification, reference being had therein to the accompanying drawings.

10 The invention comprises improvements in the depletion-detecting and indicating mechanisms, commonly termed feeler mechanisms, which are employed in looms for the purpose of forestalling complete exhaustion of the 15 supply of weft or filling contained in the working shuttle upon the lay of a loom. These mechanisms, in general, are contrived to "indicate", or "call", or "initiate", as it variously is termed, a change in the operation 20 of the loom, and heretofore have been arranged to do this upon detecting that the progressive depletion of the said supply has reached a stage decided upon as a minimum. The change involves in some cases automatic 25 replenishing of the working supply of weft or filling; in other cases, it involves stoppage of the loom.

The invention has relation more particularly to feeler-mechanisms of the measuring 30 class. Feeler-mechanisms of this class are controlled in their action by the size of the supply of weft or filling contained in the shuttle. By the improvements, a mechanism of such class is adapted to initiate, 35 prior to substantial exhaustion of the weft or filling, a series of pick-counting operations upon detecting reduction of the said supply to a measured quantity exceeding the predetermined minimum quantity, and to 40 call a change in the operation of the loom at the end of a predetermined sequence of residue-reducing picks by which the initiatory residue is woven off down to the predetermined minimum of waste.

45 By basing the action of the feeler-mechanism of a loom upon a measurement taken while there still remains a residue of weft or filling of appreciable dimensions upon the bobbin or other weft-carrier, the invention 50 obviates the delicacy and uncertainty of action prevailing when the action is based upon a measurement taken when only a thin layer comprising a comparatively few coils or turns of weft or filling remains, espe-

cially when weaving with fine weft or filling. 55 The circumstances referred to have operated, in the use of the measuring feelers heretofore in use, to bring about a practice of setting by adjustment the feeler of a loom to indicate, call, or initiate a change when actually an excess of weft or filling still remains upon the bobbin or other weft-carrier. The portion remaining upon the bobbin or weft-carrier becomes waste. The margin of safety usually provided for in practice in 65 mills entails an undesirably large percentage of waste, and consequent loss in profits.

In carrying the invention into effect I combine with means for calling a change in the operation of a loom, and a controller for 70 such means, a controller-governor normally acting through the controller to render the said means inoperative, and devices which upon detection of reduction of the working supply of weft or filling to a measured 75 amount exceeding substantial exhaustion, initiate a series of controller-governor actuating operations by which, upon the completion of a predetermined number of the said operations, the controller-governor renders said means effective to call the change. 80

The invention comprises various features which are pointed out in claims at the close of this specification.

In embodying the principles of the invention, the mechanical construction, as well as the arrangement of the parts, may be varied more or less to suit the views of the maker and user, and to meet the special needs in practice in the application and use 90 of the feeler-mechanism in which said principles are embodied.

The drawings show a feeler-device which corresponds in construction and general mode of operation with a well-known feeler-device at present in general use, and a controller which in the main is of a well-known form. Inasmuch as the principles of the invention are applicable in connection with other forms and arrangements of feeler-devices and controllers, it is to be understood that the claims that are made hereinafter are not restricted to feeler-devices and controllers like those shown in the drawings. 100

In the drawings,—

Figure 1 is a side elevation of certain parts at the feeler-side of a loom, including an illustrative embodiment of the invention. 105

Fig. 2 is a side elevation of the said embodiment and the support therefor, on a larger scale than Fig. 1.

Fig. 3 is a plan view of the parts that are shown in Fig. 1.

Fig. 4 is a plan view of the parts that are shown in Fig. 2, omitting the loom-frame, the scale being the same as that of Fig. 2.

Figs. 5 and 6 are elevation views of the parts shown in Figs. 2 and 4, partly in section on line 5, 5, of Fig. 3, looking in the direction indicated by the arrows near the ends of such line, and illustrating different positions. A shuttle and bobbin are shown in Fig. 6.

The feeler-device shown in the drawings comprises the spring-actuated slide-bar 1 having its rear end shaped to constitute a feeling-head 2, the actuator 3 mounted 10 pivotally at 4 upon the slide-bar, and the adjustable bunter 5 carried by the actuator 3. At 6 is the feeler-stand or casing, having guide-ways in which the slide-bar and its forward extension 1^a work, and at 7 is the 20 expanding spiral spring contained within the said feeler-stand or casing and by means of which the slide-bar 1 is caused to assume its normal rearward position. As a convenient means of supporting the feeler-device in working position, the feeler-stand or 30 casing 6 is shown attached to a carrier-stand 71, which is secured by a bolt or bolts 8 to a flange 9 of the usual bracket or plate 10 attached to loom-frame 11 at one end 35 of breast-beam 12, Fig. 3, the said bracket or plate having the slot 13 within which the shipper-handle 14 (Fig. 3) works.

15 is the spring-supported pin upon the upper end of which the forwardly extending arm of the actuator 3 rests, and by which the actuator is held normally in an inoperative position, with the said arm elevated and the bunter 5 rearward. The pin 15 is carried and guided by a small casing 16 in connection with an arm 17 of the top of feeler-casing 6, and its actuating spring 18 is contained within such casing.

Fig. 3 shows, in position for presentation against the feeling-head 2, a wound mass 50 19 of weft or filling of full diameter carried by the bobbin 20 contained within the shuttle 21, the latter occupying in the figure the shuttle-box upon lay 22 at the side of the loom at which the feeler is located. 55 Figs. 3 and 6 show the opening 23 in the front-plate 24 of the said shuttle-box, and the opening 25 in the front wall of the shuttle-body, through which the feeling-head enters the shuttle to feel against the 60 weft-mass.

As heretofore, while the weft-mass 19 is of sufficient diameter, as in Fig. 3, the surface thereof will engage with the feeling-head 2 during the advance of the lay, and 65 push the feeler forward without permitting

engagement between the front wall of the shuttle-body and the bunter 5. Every time this action takes place, the actuator will retain its normal, inoperative, position upon the feeler as it goes forward in unison with the latter, and the stroke thus communicated to feeler and actuator will be an idle one. When the portion of the weft-mass that is presented to the feeling-head is reduced in diameter to an extent permitting the head of bunter 5 to engage with the front wall of the shuttle before the reduced weft-mass engages the feeling-head 2, the pressure of such wall against the said head will have the effect of turning the actuator 3 upon 70 pivot 4, as in Fig. 6, so as to depress the forwardly-extending arm of the actuator into operative position. In practising my invention, the bunter 5 is so adjusted that the depression just referred to will take 75 place at a somewhat earlier stage than heretofore in the progressive depletion of the weft or filling mass. This depression of the said arm is utilized to actuate the controller-governor, primarily for pick-counting purposes and finally for causing or permitting the controller to call into action the parts that are more immediately concerned in bringing about the change in the operation 80 of the loom.

The controller for the said parts is itself indirectly under the control of the feeler-device through the controller-governor, which latter is controlled directly by means of the feeler-device, through the actuator 85 100 when the latter is given its depressed position in the feeling action. In the present instance, the controller comprises a horizontal rockshaft 26 extending in the direction of the length of the breast-beam and 105 mounted in bearings provided in connection with a small stand 27 that is attached to the front of the breast-beam. At its outer end the controller-rockshaft is combined operatively with the controller-governor; at its 110 inner end it is combined operatively with the parts for bringing about the change. In this instance the rockshaft 26 at its outer end has an arm 28, 28^a, through which it is controlled by the controller-governor, and 115 normally held in a position which keeps elevated an arm 29 at its inner end; at its inner end it has the arm 29, which is provided with an inwardly bent crank-pin 30 entering a longitudinal slot 31, Fig. 1, in a catch 32 120 that is hung at its front end by means of a pivot 33 upon an arm 34 mounted upon the controlling rockshaft 35 for the replenishing instrumentalities, or stopping mechanism, etc. As usual, so long as the said 125 controller is kept in its normal position with arm 29 elevated it keeps the catch raised out of the path of a striker 36 carried by the weft-hammer 37, but when the controller is permitted or caused to turn so as to lower 130

the said arm, the turning movement of the controller permits the catch to enter the said path. When the striker finds the catch in its path, it engages with the catch and pushes the latter forward, thereby rocking the controlling rockshaft 35 and calling the change. The invention is not restricted to the employment of this particular means of controlling through a controller the parts for bringing about a change in the operation of a loom.

The controller-governor comprises a member, in this instance a wheel 38, which through its engagement with an arm of the controller, in this case the arm 28, 28^a, governs the controller and catch, and thereby governs the engagement of the catch by the striker. The said member preferably, as herein, is so constructed and combined with the said arm that normally it keeps the catch out of the path of the striker. Also, so that through its movement it permits the controller to operate at a predetermined point in such movement to place the catch in the path of the striker. This general mode of governance is not in all cases essential to the invention when a rotary controller-governor is employed. In this instance the wheel 38 is a peripheral cam which by engagement with a lug 39 projecting from arm 28, 28^a, keeps such arm elevated, and thereby locks the controller in a position in which it holds the catch out of the path of the striker, until a notch 40 in the wheel is presented to the lug. Thereupon the controller turns so that the lug enters into the notch, and this turning movement is accompanied by movement of the catch into the path of the striker.

The actuation of the controller-governor by means of the feeler-device may be effected in various ways, within the broad principles of my invention. Herein, it is produced through the engagement of the actuator 3 with a ratchet-wheel 41 when the shuttle engages the bunter 5 so as to depress the actuator as in Fig. 6 and cause it to occupy a depressed position as the feeler goes forward. The ratchet-wheel is combined operatively with the wheel 38 in manner to cause the latter to turn when the former is caused to turn. The two wheels are shown as fast with each other. Each time the actuator occupies a depressed position as the feeler goes forward, the engagement of the actuator with the ratchet-wheel produces a partial turning of the controller-governor; until by a number of repetitions of the step-by-step turning movement the notch 40 is brought around to the lug 39 and the latter enters into the notch. A detent-spring 42 that engages with the teeth of the ratchet-wheel serves to prevent retrograde turning of the controller-governor.

Stating the action briefly: every time the

weft-mass contained in the shuttle pushes the feeler forward through contact with feeler-head 2 without permitting the shuttle-body to engage with the bunter 5, the actuator 3 will go forward without engaging the ratchet-wheel, and consequently the controller-governor will remain in its starting position shown in Figs. 1, 2, 5. When, however, the depletion of the weft-mass reaches a stage in which the feeling-end 2 will enter so far into the shuttle that the shuttle-body will be permitted to strike against bunter 5 and turn actuator 3 on its pivot 4, the free end of the actuator will be caused to engage with the teeth of the ratchet-wheel, and then through the forward movement communicated to the feeler and actuator the actuator will be caused to turn the controller-governor around part way, as in Fig. 6. At subsequent feeling actions following returns of the shuttle to the feeler-side of the loom, the step-by-step turning of the controller-governor will proceed until lug 39 enters notch 40, such entry being followed by engagement of the catch by the striker, this bringing about the change.

It is desirable to secure the advantage of basing upon an initiatory residue of weft or filling of conveniently large dimensions the critical measurement by which the action of the controller-governor is initiated. Accordingly, preferably, I set by adjustment the bunter 5 of the feeler-device to receive the impact and pressure of the shuttle-body while there still remains in the shuttle an amount of weft or filling sufficient to permit a fairly considerable number of picks of the shuttle to take place before the predetermined absolute minimum is reached, and I provide for an action of the controller-governor permitting a sequence of residue-reducing picks preferably including two or more returns of the shuttle to the feeler-side of the loom. A smaller number of residue-reducing picks will not provide, in some cases, for a sufficient and practical difference between the initiatory residue and the absolute or final minimum.

The number of pick-counting operations prior to calling the change in the operation of the loom may be varied by obvious changes in the construction. More than one notch may be provided in the wheel 38, so that a change may be brought about by less than a complete rotation of the controller-governor. In the case of fine yarn a greater number of the pick-counting operations will be necessary than in the case of coarse yarn.

I provide means for automatically resetting the controller-governor. In this instance the lug 39 of arm 28, 28^a, is provided upon the portion 28^a of such arm, and the said portion is furnished with a downturned toe 43. For cooperation with the said toe the bay is furnished with a bunter 44, Figs. 130

1 and 3, that projects forwardly from the lay-beam. So long as a full portion of the periphery of wheel 38 is presented under lug 39 and the arm is held elevated thereby, 5 the toe is kept raised out of the path of the bunter 44. When the final step-movement of the wheel is caused to take place, just as the lay completes a beating-up movement and the notch 40 thereby is presented under 10 the lug so that the arm is permitted to drop the toe 43 passes down at the rear of the upturned engaging end of the bunter 44, which at that instant is in its most forward position. The ensuing rearward movement 15 of the lay causes the bunter 44 to raise the arm as the said bunter passes backward under and past the beveled-off lower end of the toe, and then the arm drops again, with the lug 39 within notch 40. As the lay beats 20 up the next time, the end of bunter 44 encounters the toe 43, and drives the toe and the member 28^a of the arm forward. To permit member 28^a to move relative to member 28 it is mounted slidably upon the latter, 25 with loops 45, 45, of one member embracing the other member. A screw 46 carried by member 28^a works in a longitudinal slot 47 in member 28, and a contracting spiral spring 48 engaged with the said screw and 30 with a pin 49 projecting from member 28 exerts its tension to hold member 28^a in its rearwardly extended position as far as permitted by the engagement of screw 46 with the rear end of slot 47. Spring 48 yields to 35 permit the member 28^a to be driven forward upon member 28. As member 28^a goes forward, the straight back of the lug 39 acts against the front wall of notch 40 and rotates the wheel 38 forward a step farther, 40 thereby giving the wheel its starting position. As the lay goes rearward again, spring 48 acts to pull member 28^a rearward, and the inclined rear side of the lug rides up over the corner at the top of the rear wall 45 of notch 40, so that the lug passes out upon the periphery of the wheel and remains resting thereon. Detent 41 holds wheel 38 from reverse turning movement as this action takes place.

50 In some cases I may so construct and combine the parts that the weft-feeler device will serve to give to the wheel 38 its first movement from the starting position thereof, and other devices will thereupon act to 55 communicate to the wheel its successive pick-counting movements.

I claim as my invention:—

1. In a loom, the combination with means for calling a change in the operation thereof, and a controller for such means, of a rotary controller-governor, and a feeler-device operatively combined with the said controller-governor and adapted to turn the same step-by-step on successive feeling actions following detection of depletion of

the working weft-supply to a predetermined initiatory residue, and by such turning render the said means operative to call a change after a predetermined sequence of residue-reducing picks.

2. In a loom, the combination with means for calling a change in the operation thereof, and a controller for such means, of a controller-governor engaging with the controller to give it normally a position corresponding with functional inactivity of the said means, said controller-governor having a series of ratchet teeth, and a feeler-device adapted to actuate said controller-governor through said ratchet teeth to render the controller and said means effective to call the change after a predetermined sequence of residue-reducing picks succeeding detection of a predetermined initiatory residue of weft or filling.

3. In a loom, the combination with means for calling a change in the operation thereof, and a controller for such means, of a rotary controller-governor engaging with the controller to give it normally a position corresponding with functional inactivity of the said means, and a feeler-device adapted to actuate said controller-governor to render the controller and said means effective to call the change after a predetermined sequence of residue-reducing picks succeeding detection of a predetermined initiatory residue of weft or filling.

4. In a loom, the combination with means for calling a change in the operation thereof, of a rotary governor operatively combined with and governing the said means, and means adapted to turn the said rotary governor step-by-step through a succession of picks following detection of depletion of the working weft-supply to a predetermined initiatory residue, and through such turning render the said means operative to call a change after a predetermined sequence of residue-reducing picks.

5. In a loom, the combination with means for calling a change in the operation thereof, of a rotary governor operatively combined with and governing the said means, and a feeler-device operatively combined with said rotary governor and adapted to turn the same step-by-step through a succession of feeling actions following detection of depletion of the working weft-supply to a predetermined initiatory residue, and through such turning render the said means operative to call a change after a predetermined sequence of residue-reducing picks.

6. In a loom, the combination with means for calling a change in the operation thereof, of a cam-wheel, means adapted to turn the said cam-wheel step-by-step through a succession of picks following detection of depletion of the working weft-supply to

2. predetermined initiatory residue, and means through which said cam-wheel controls the said means for calling a change and renders the latter operative to call the 5 change after a predetermined sequence of residue-reducing picks.
3. In a loom, the combination with means for calling a change in the operation thereof, of a cam-wheel, a ratchet-wheel operatively combined therewith, a weft-feeler, means connected therewith for turning the said cam-wheel on successive feeling actions detecting reduction of the working supply of weft or filling to and below a predetermined initiatory residue, and means through which after a predetermined sequence of residue-reducing picks the said cam-wheel renders said means for calling a change operative to call a change.
4. In a loom, the combination with means for calling a change in the operation thereof, of a cam-wheel, a ratchet-wheel operatively combined therewith, a weft-feeler, means connected therewith for turning the said cam-wheel on successive feeling actions detecting reduction of the working supply of weft or filling to and below a predetermined initiatory residue, and a controller controlled by the said cam-wheel and itself controlling the said means for calling a change.
5. In a loom, the combination with means for calling a change in the operation thereof, of a cam-wheel, a ratchet-wheel operatively combined therewith, means adapted to turn the said ratchet-wheel and cam-wheel step-by-step through a succession of picks, following detection of depletion of the working weft-supply to a predetermined initiatory residue, and a controller controlled by the said cam-wheel and itself controlling the said means for calling a change.
6. In a loom, the combination with means for calling a change in the operation thereof, and a controller for said means, of a rotary governor which controls said controller, devices which upon detection of reduction of the working supply of weft or filling to a predetermined initiatory residue initiate 45 and cause a succession of step-by-step movements of the said governor and thereby through the governor and controller, after a predetermined series of residue-reducing picks, render said means for calling a change operative to call a change, and means for placing the said rotary governor in starting position for the next succession of movements.
7. In a loom, the combination with means for calling a change in the operation thereof, of a cam-wheel, a ratchet-wheel operatively combined therewith, a weft-feeler, means connected therewith for turning the said cam-wheel on successive feeling actions detecting reduction of the working supply of weft or filling to and below a predetermined initiatory residue causes progressive movement of said governor and thereby through the governor and controller renders said means for calling a change operative to call a change after a predetermined sequence of residue-reducing picks, and means for placing said rotary governor in starting position for the next succession of movements.
8. In a loom, the combination with means for calling a change in the operation thereof, of a rotary governor operatively combined with and governing the said means, means adapted to turn the said rotary governor step-by-step through a succession of picks following detection of depletion of the working weft-supply to a predetermined initiatory residue, and through such turning render the said means operative to call a change after a predetermined sequence of residue-reducing picks, and means for placing said rotary governor in starting position for the next succession of turning movements.
9. In a loom, the combination with means for calling a change in the operation thereof, of a cam-wheel, means adapted to turn the said cam-wheel step-by-step through a succession of picks following detection of depletion of the working weft-supply to a predetermined initiatory residue, means through which said cam-wheel controls the said means for calling a change and renders the latter operative to call the change after a predetermined sequence of residue-reducing picks, and means for placing said cam-wheel in starting position for the next succession of turning movements.
10. In a loom, the combination with means for calling a change in the operation thereof, and a controller for such means, having an arm provided with a relatively movable member, of a cam-wheel engaging with said member to govern the controller, means adapted to turn said cam-wheel step-by-step through a succession of picks following detection of depletion of the working weft-supply to a predetermined initiatory residue and thereby through the cam-wheel and controller after a predetermined series of residue-reducing picks render said means for calling a change operative to call a change, and means for acting through said movable member to place the cam-wheel in starting position.
11. In a loom, the combination with means for calling a change in the operation thereof, and a controller for said means, of a rotary governor which controls said controller, a weft-feeler which by a series of feeling actions following detection of reduction of the working supply of weft or filling to a pre-

predetermined series of residue-reducing picks render said means for calling a change operative to call a change, and means moving with the lay adapted to actuate said movable member and through engagement of the latter with the wheel at the camportion place the wheel in starting position.

16. In a loom, the combination with a lay, a weft-feeler, and means for calling a change in the operation of the loom, of a rotary controller-governor provided with a notch and adapted to be operated by the said weft-feeler, a controller for the said means provided with an arm having thereon a spring-controlled movable member furnished with a lug normally resting against the controller-governor and adapted to enter the said notch when the latter is presented in position to receive the lug, such entry permitting action of the controller by which the means for calling a change is rendered effective to call the change, and a bunter moving with the lay, and adapted to engage the said member when the lug occupies the notch and as a result of such engagement actuate the member to turn the controller-governor into starting position.
17. In a loom, the combination with a lay, a weft-feeler, and means for calling a change in the operation of the loom, of a rotary controller-governor provided with a notch and adapted to be operated by the said weft-feeler, a controller for the said means provided with an arm having thereon a spring-controlled movable member fur-

nished with a lug normally resting against the controller-governor and adapted to enter the said notch when the latter is presented in position to receive the lug, such entry permitting action of the controller by which the means for calling a change is rendered effective to call the change, and a bunter moving with the lay, adapted to draw out from under the said member when the latter drops behind the same, and to engage in the advance of the lay with the dropped member and as a result of such engagement actuate the member to turn the controller-governor into starting position.

18. In a loom, the combination with means for calling a change in the operation thereof, and a controller for such means, of a controller-governor coöperating with said controller and having a series of ratchet teeth, a normally ineffective actuator adapted to coöperate with said ratchet teeth to move the controller-governor step by step, and a feeler device which renders said actuator effective to engage said ratchet teeth so that the said change controlling means are brought into action after a predetermined sequence of picks succeeding detection of a predetermined initiatory residue of weft.

In testimony whereof I affix my signature in presence of two witnesses.
